CLAIM

The ornamental design for a height adjustable desk, as shown and described.

DESCRIPTION

FIG. 1 is a first perspective view of a height adjustable desk showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof.
